US00D449883B1

(12) **United States Design Patent**
McDonald et al.

(10) Patent No.: **US D449,883 S**
(45) Date of Patent: ** Oct. 30, 2001

(54) **OXYGEN DELIVERY SYSTEM**

(75) Inventors: **Lee McDonald, Maurice Lavimodiere**,
both of Barrie (CA)

(73) Assignee: **Southmedic Incorporated**, Barrie (CA)

(**) Term: **14 Years**

(21) Appl. No.: **29/136,099**

(22) Filed: **Jan. 24, 2001**

(51) LOC (7) Cl. **29-02**
